UNITED STATES PATENT OFFICE.

PAUL COATS, OF LAPRAIRIE, ILLINOIS.

BROODER.

No. 811,484.

Specification of Letters Patent.

Patented Jan. 30, 1908.

Application filed May 6, 1905. Serial No. 259,175.

To all whom it may concern:

Be it known that I, PAUL COATS, a citizen of the United States of America, residing at Laprairie, in the county of Adams and State 5 of Illinois, have invented new and useful Improvements in Brooders, of which the following is a specification.

The invention relates to an improvement in brooders of simple construction and operation.

The main object of the present invention resides in the production of a brooder designed for adjustment to accommodate the growing fowls and adapted to readily retain 15 the heat directed thereto, whereby the efficiency and usefulness of the brooder are materially increased.

The preferred details of structure are illustrated in the accompanying drawings, where- 20 in—

Figure 1 is a vertical central section of a brooder constructed in accordance with my invention. Fig. 2 is a bottom plan of the hover-board, showing the curtain in place 25 thereon.

Referring particularly to the drawings, my improved brooder comprises a base-board 1, from which vertically extends a perforate cylinder 2, such as screen-cloth or the like, 30 and within which cylinder the heating medium is arranged, as is usual in devices of this character.

3 represents the hover-board, preferably circular in plan and provided with a depend- 35 ing cylindrical flange 4', arranged centrally thereof and of a size to snugly embrace the heat-cylinder 2, projecting from the base. To the lower side of the hover-board I secure a heat-retaining medium 4, preferably sheep- 40 skin, with the wool side thereof facing to- 45 ward the base-board 1 or within the brooder. A circular flange 5 is secured to the periphery of the hover-board, preferably projecting above and below the surface of the board.

45 A ring 6, preferably of wire or the like, is ar- 50 ranged to frictionally engage the flange 5 thereon the outer side thereof, and to this ring is secured a curtain 7, of suitable flexible material and designed to depend toward and 55 contact with the base 1, it being understood that the curtain incloses the space within the plane of the hover-board.

The construction shown and described

provides a brooder having a hover-board 55 slidably connected with the base and an inclosing curtain slidably connected with the hover-board.

The use of my invention is obvious from the above description, it being understood that the hover-board is vertically adjusted 60 with relation to the base through the sliding engagement of the cylindrical flange 4 and the heat-cylinder 2, the curtain-ring 6 being adjusted vertically with relation to the flange 5 of the hover-board to insure contact of the 65 bottom of the curtain with the base in all positions of said hover-board. The sheepskin 4, with the wool next the brooding-chamber, is effective for receiving and maintaining an even temperature within the brooder, the 70 wool acting in a measure as a substitute for the natural feather covering of the mother fowl. The brooder may be adjusted as desired to accommodate the growing fowls, the adjustment of the curtain insuring an inclos- 75 ing medium at all times.

It is to be understood that I contemplate the use of any desired or preferred form of heater, as such in its detail, so far as the present invention is concerned, is immaterial. 80

Having now described my invention, what I claim as new, and desire to secure by Letters Patent, is—

1. A brooder comprising a base and a vertical adjustable hover-board, and an adjustable inclosing curtain.

2. A brooder comprising a base, a fleece-lined hover-board vertically adjustable with relation to the base, and an inclosing curtain vertically adjustable with relation to the 90 hover-board.

3. A brooder comprising a base, a perforate guard-cylinder projecting from the base, a hover-board having a depending cylindrical flange to embrace said guard-cylinder, and an 95 inclosing curtain vertically adjustable with relation to said hover-board.

4. A brooder comprising a base provided with a vertically-projecting perforate guard-cylinder, a hover-board slidably connected to said guard-cylinder, a vertically-arranged flange secured to the periphery of the hover-board, a curtain-ring frictionally and slidably engaging said flange, and a curtain depending from said ring.

5. A brooder comprising a base provided

with a vertically-projecting perforate guard-cylinder, a fleece-lined hover-board slidably connected to said guard-cylinder, a vertically-arranged flange secured to the periphery of the hover-board, a curtain-ring vertically and slidably engaging said flange, and a curtain depending from said ring.

In testimony whereof I affix my signature in presence of two witnesses.

PAUL COATS.
